UNITED STATES PATENT OFFICE.

JOHN V. SPRAGUE, OF PITTSBURGH, PENNSYLVANIA, ASSIGNOR OF ONE-HALF TO
HARRY W. CROSS, OF BELLEVUE, PENNSYLVANIA.

HUMIDOR.

1,414,381.

Specification of Letters Patent. Patented May 2, 1922.

Application filed January 8, 1917. Serial No. 141,081.

To all whom it may concern:

Be it known that I, JOHN V. SPRAGUE, a citizen of the United States, and residing in the city of Pittsburgh, in the county of Allegheny and State of Pennsylvania, have invented or discovered new and useful Improvements in Humidors, of which the following is a specification.

My invention consists in a new and improved 10 humidor for moistening the contents of cases and other compartments used for the display or storage of cigars and other forms of tobacco.

The object I have in view is as follows: 15 the provision of a humidor device which will evaporate water and disseminate moisture throughout the interior of the compartment when required; which may be readily turned on or off; which will not occupy valuable room within a display case; which will be ornamental without being obtrusive, and which may be used as a source of interior illumination for the display case.

These advantageous features are characteristic 25 of my improved humidor, which I will now proceed to describe.

In the accompanying drawings, Fig. 1 is an end view of a cigar display case provided with one of my improved humidors, 30 and Fig. 2 is an enlarged elevation of the latter with the bath shown in vertical section.

The following is a detailed description of the drawings.

35 A represents a compartment intended to contain tobacco products, shown as a cigar case provided with glass panels.

B represents a tubular or hollow wall bracket firmly attached, as by plate 1 and 40 screws 2, to the inner surface of the back wall of the case A near the top of the case.

C is an incandescent bulb socket mounted on the depending arm of the bracket B, and electrically connected with the lead-in wires 45 3 and 4 which extend through the wall of the case A and the interior of the bracket B.

D is a spring holder mounted on the depending socket C in which is secured the curled mouth flange 5 of a spherical bath

50 E of transparent or, preferably, translucent glass.

F is an incandescent bulb screwed into the socket C and depending within the bath E.

The bath E is filled with water or other liquid nearly to its top but sufficiently below the top of the bath to avoid the possibility of short circuiting the socket. 55

The holder D is provided with a plurality of ports 6 for the escape of moisture and to permit the supply of water in the bath E 60 to be replenished.

When the current is turned on, the heat of the bulb causes the water in the bath to evaporate and rise as moisture into the top of the case and descend and permeate the 65 entire interior of the case. When the air within the case is sufficiently moistened, the current may be turned off.

The advantages of my improved humidor are many, and, among them, may be mentioned the following:

The humidor, being suspended in the upper part of the case from the vertical wall, does not encumber the floor or shelves and thus reduce the display capacity of the case. 75 The humidor is slightly and ornamental but not obtrusive. The humidor discharges the moisture into the upper part of the case whence it descends naturally and moistens the goods. Thus no fan or other air agitating device is required. The humidor illuminates the case with a soft, diffused glow which advantageously displays the goods without an unpleasant glare. During holiday seasons the liquid may be colored to 80 add to the display a seasonable attractiveness.

What I desire to claim is:—

1. A combined humidifier and illuminating device comprising a supported incandescent bulb, a supporting disk carried by and fixedly secured with respect to the incandescent bulb and having a resilient gripping member at the peripheral edge thereof, a translucent fluid reservoir having an open 90 top, said top adapted to fit within the peripheral edge of the supporting disk and to be held therein by the resilient gripping member thereby suspending the reservoir with the incandescent bulb immersed with 95 in the fluid therein.

2. A combined humidifier and illuminat-

ing device comprising a supported incandescent bulb, a supporting member fixedly secured to the incandescent bulb and having gripping means at the outer edge thereof, 5 a glass reservoir having an open top, said top adapted to fit within the outer edge of the supporting member and to be held there-

in by the gripping means thereby suspending the reservoir with the incandescent bulb immersed therein.

10

Signed at Pittsburgh, Penna., this 4th day of January, 1917.

JOHN V. SPRAGUE
